US0D1018190S

(12) **United States Design Patent** (10) **Patent No.:** **US D1,018,190 S**
(45) **Date of Patent:** **** Mar. 19, 2024**

(54) **LID OF FOOD PROCESSING POT**

(71) Applicant: **FOSHAN SHUNDE MIDEA ELECTRICAL HEATING APPLIANCES MANUFACTURING CO., LTD.**, Foshan (CN)

(72) Inventor: **Mao Tan**, Foshan (CN)

(73) Assignee: **FOSHAN SHUNDE MIDEA ELECTRICAL HEATING APPLIANCES MANUFACTURING CO., LTD**, Foshan (CN)

(**) Term: **15 Years**

(21) Appl. No.: **29/780,519**

(22) Filed: **Apr. 25, 2021**

(30) **Foreign Application Priority Data**

(57) **CLAIM**

The ornamental design for a lid of food processing pot, as shown and described.

DESCRIPTION

FIG. 1 is a front elevation view of a lid of food processing pot, showing my new design;

FIG. 2 is a back elevation view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken lines in the figures depict portions of the lid of food processing pot that form no part of the claimed design.

1 Claim, 7 Drawing Sheets
